UNITED STATES PATENT OFFICE.

WILLIAM S. GRAHAM AND FREDERIC L. DEWEY, OF CANTON, ILLINOIS, ASSIGNEES TO PARLIN & ORENDORFF COMPANY, OF CANTON, ILLINOIS, A CORPORATION OF ILLINOIS.

REVERSIBLE DISK HARROW.

No. 875,805.

Specification of Letters Patent.

Patented Jan. 7, 1908.

Application filed June 6, 1906. Serial No. 320,463.

To all whom it may concern:

Be it known that we, WILLIAM S. GRAHAM and FREDERIC L. DEWEY, residents of the city of Canton, county of Fulton, and State 5 of Illinois, have invented certain new and useful Improvements in Reversible Disk Harrows, of which the following is a specification.

This invention relates in part to the frame 10 structure, in part to the means used to tilt the gangs with relation to the horizontal and in part to the provision for reversing the disks, so as to throw to or from the center. The invention is exemplified in the structure 15 hereinafter described and it is defined in the appended claims.

In the drawings forming part of this specification Figure 1 is a plan view of a harrow embodying our improvements, one gang being 20 swung in such manner that, when set at the proper angle, it will throw the soil toward the center and the other gang being reversed, or arranged to throw the soil from the center, Fig. 2 is a section vertically through the 25 center of the vertical pivot for one of the gangs, showing how the arch of the gang is held in position to control the relation of the gang to the surface of the soil. Fig. 3 is a plan of the saddle that acts as a pivot and as 30 a part of the arch clamp. Fig. 4 is a plan of the combined clamp plate and arm bracket which aids in clamping the gang arch and provides connections for the arms used to swing the gangs horizontally.

The tongue of the harrow is shown at 1, at 2 and 3 are shown parallel cross bars which comprise essential elements of the frame and at 6 and 7 are shown brace bars which extend from the ends of the cross frame obliquely 40 forward to the tongue. The ends of cross bars 2 and 3 are bent at right angles, as shown at 4 and 5, and the brace bars are bent to conform to the turned ends of the cross bars. The bent ends of the cross 45 bars are turned toward each other, at each end, the ends of the brace bars overlap the bent ends of the cross bars and bolts connect the cross bars with the brace bars and the brace bars with the tongue. Brackets 8 are 50 attached to the brace bars between the cross

frame and the tongue, rack brackets 9 and 10 are secured to the tongue in line with brackets 8 and rock shafts 11 and 12 journal in the brackets 8 and in bearings in the rack brackets. The shafts 11 and 12 are non- 55 circular and arms 13 and 14 are clamped one on each of the shafts.

The disks 29 are arranged in two gangs, each gang being journaled on an independent shaft, and arch bars 27 are secured to bearings 60 on the gang shaft, an arch to each gang. The upper parts of the arches form arcs of circles and they are clamped in different positions to vary the horizontal arrangement 65 of the gangs.

Secondary frames 17 are secured to the cross bars 2 and 3 by means of bolts 19 and they have circular vertical bearing rings 18 for the pivots of the gangs. The secondary frames may be set farther apart or closer 70 together in order to properly adjust the space between gangs and when they are in place they are rigid with relation to the cross frame.

Saddles 20 are adapted to sit on the curved 75 summits of the arch bars and each is provided with an upward-extending circular bearing 21 which is rotatable in a bearing ring 18 of a secondary frame 17. A cap plate 22 fits on the upper end of the pivot 80 extension of each saddle plate and it overlaps the ring 18 to hold the saddle pivot in the secondary frame. A clamp plate 24 fits against the under surface of each arch bar, opposite the saddle, and bolts 23 extend up- 85 ward through the clamp plate, on opposite sides of the arch bar, and pass through holes in the cap plate 22. Nuts on the ends of the bolts above the cap plate, clamp the arch bar between the saddle and the clamp plate 90 and hold the arch in any desired position.

A lateral extension of the clamp plate lies alongside the arch bar and extends in opposite directions from the center of the clamp plate, as shown at 25 and 26 in Fig. 4. 95 These extensions form connections for a controlling arm 28, and they provide means for extending the arm in either direction from the arch pivot. Link rods 15 and 16 connect the controlling arms 28 with arms 13 100

and 14 on shafts 11 and 12, and lock levers 30 and 31 provide means for rocking the shafts and for holding them in place.

When the harrow is in operation both 5 gangs are set to throw either toward the center or from the center and are inclined to present the concave surfaces of the disks obliquely to the soil.

When it is desired to throw the soil toward the center, the gangs are both set as 10 shown at the upper end of Fig. 1, the controlling arm 28 of the lower gang being shifted to end 26 of the connection plate to give it the proper inward extension. Under 15 these conditions the lock lever 31 will be thrown forward, the same as lever 30, while the gangs are in their shown alinement, and the levers will both be carried backward, toward seat 34, to give the proper cutting obliquity to the disks. When it is desired to 20 reverse the disks, the controlling arms are disconnected, the gangs are turned end for end, as shown at the lower end of Fig. 1, and the controlling arms are re-connected with 25 the connection plates at the opposite ends thereof. This will cause both lock levers to incline backward, while the gangs are in alinement, and the levers will be pushed forward to give proper obliquity to the disks.

30 The inner ends of the gangs are carried forward when the soil is thrown toward the center and are carried backward when it is desired to throw the soil from the center. The extent of movement from one extreme 35 to another is considerable and it has heretofore been impossible to get the required motion in the controlling levers without excessive throw of the levers or excessive work on account of length of the work-ends of the 40 levers. But by shifting the arms 28 to the front of the vertical pivots of the gangs when the soil is thrown from the center, and reversing the arrangement while throwing to the center, the motion of the controlling levers is no greater than if the gangs were not 45 reversible, and sufficient force to control the gangs may be readily developed by the comparatively short swing of the levers.

The clamped arch bars provide simple and 50 effective means for adjusting the gangs horizontally and the positions of the clamp bolts on opposite sides of the arch bar obviates the necessity of slotting the bar.

The main frame is simple in construction 55 and quite strong in proportion to its weight. The secondary frame is easily secured to the main frame and adjusted crosswise thereof, and when it is secured in place it is perfectly stable. The brace bars strengthen 60 the frame while providing bearings for the outer ends of the rock shafts and the rock shafts provide for all the sidewise shift the rock arms may ever need. The tongue is secured to the cross bar 2, by bracket 32,

and so the entire frame structure is in the 65 nature of a truss.

We claim as new and desire to secure by Letters Patent:

1. In a reversible disk harrow, the combination of a pair of parallel cross bars, a 70 tongue connected to the cross bars at the longitudinal center thereof, oblique brace bars secured to in-turned ends of the cross bars and to the tongue, gang-carrying secondary frames secured to the parallel bars, 75 and gang-controlling rock shafts journaled in bearings on the tongue and on the brace bars, substantially as described.

2. In a reversible disk harrow, the combination of a cross frame, disk gangs pivotally attached to the cross frame, a tongue connected with the cross frame at the longitudinal center thereof, brace bars extending obliquely from the ends of the cross frame to the tongue, and gang-controlling rock shafts 85 journaled in bearings attached to the tongue and to the brace bars, substantially as described.

3. In a reversible disk harrow, the combination of a cross frame, disk gangs pivotally attached to the cross frame, a tongue attached to the longitudinal center of the cross frame, brace bars extending obliquely from the ends of the cross frame to the tongue, rack brackets secured to opposite 90 sides of the tongue, brackets attached to the brace bars, rock shafts journaled in the brackets on the cross bars and the brackets on the tongue, lock levers for the rock shafts 95 coaxing with the racks, arms on the shafts 100 and link rods connecting the arms with the disk gangs, substantially as described.

4. In a reversible disk harrow, the combination with a frame, a circular bearing journaled in said frame and having an arched lower surface, and a disk gang, of an arch bar secured to said disk gang and adapted to conform to the arched lower surface of said circular bearing, a clamp plate adapted to bear against the under side of said arch 105 bar, and means for adjustably clamping said arch bar between said circular bearing and said clamp plate, substantially as described.

5. In a reversible disk harrow, the combination of a frame having a vertical journal bearing, a disk gang, an arch bar attached to the disk gang, a clamp saddle conforming to the upper surface of the arch and having an upward - extended pivot conforming to the journal bearing of the frame, a clamp 115 plate adapted to fit the under surface of the arch, a cap plate for the pivotal extension of the clamp saddle, said cap plate being projected over the journal bearing, and bolts 120 extended through the clamp members and 125 the cap plate on opposite sides of the arch bar, substantially as described.

6. In a reversible disk harrow, the com-

bination of a frame, a pair of disk gangs
swung on vertical pivots in the frame, a horizontal
connection-plate to one side of the
axis of the disks, said plate extending length-
wise of the axis of the gang in both directions
from the pivot thereof, an arm for each gang
adapted to be connected with either exten-
sion of the connection-plate, levers in front
of the gangs, and connections between the

levers and the arms, substantially as de- 10
scribed.

In testimony whereof we sign our names
in the presence of two subscribing witnesses.

WILLIAM S. GRAHAM.
FREDERIC L. DEWEY.
